SOAP DISPENSER

Anthony Tucci, 707 South St., Utica, N.Y.

Filed Oct. 30, 1958, Ser. No. 770,723

3 Claims. (Cl. 222—158)

This invention relates to dispensers for powdered, granulated and the like materials and more particularly to a powdered soap dispenser for use with conventional soap powder boxes and the like.

With the advent of automatic washing machinery and the like in the laundry industry and particularly in the home laundry industry it has become increasingly important to supply the precise amount of soap to the machine as indicated by the manufacturer. This has meant that the housewife has to measure out from the standard soap box, which is usually a rectangular container somewhere in the neighborhood of two-inches by eight-inches by ten- or fifteen-inches, into a measuring cup or the like the exact amount of soap and then place it into the washing machine. Since soap sometimes tends to stick together, much mess and bother is often encountered since the soap will sometimes pour suddenly and at other times not pour at all so that very often excess soap is spilled all over. Also, when more soap than is wanted is obtained, it is very difficult to get it back in the box since most of the modern boxes have a relatively small pouring spout or opening.

According to the present invention I have provided a soap dispenser that may be easily applied to any conventional soap box and will measure the desired amount of soap and will then dispense it to the washing machine all without any fuss and with no overflow or waste.

It is an object of the present invention to provide an improved soap dispenser attachment for conventional powdered and granulated soap boxes. It is another object of the present invention to provide a simple and foolproof attachment for soap boxes that will permit measuring and dispensing of soap therefrom without spilling. It is another object of the present invention to provide a soap dispenser for use with soap-containing boxes or cartons which permits accurate measuring and dispensing of the desired amount of soap without loss. These and other and further objects will be in part apparent and in part pointed out as the specification proceeds.

In the drawings:

Figure 1 is a side-elevation of the present invention attached to a soap box and shown in the filling or measuring position in which the soap is being drawn from the box into the dispenser to the desired amount;

Figure 2 is a view similar to Figure 1 showing the soap box and dispenser in the soap-dispensing position with the soap falling into the washing machine;

Figure 3 is a mid sectional view of the dispenser shown in Figure 2.

Referring now to Figures 1 and 2, the soap dispenser 10 comprises generally a container 12 having a receptacle portion 14, a dispenser portion 16 and a measuring portion 18, all made of a transparent plastic or other simple, cheap material.

The receptacle portion 14 comprises generally a rectangular sided box adapted to receive therein the soap box 21 within the four flanges 20 which are somewhat

2

resilient. Flanges 20 have impressions or dimples 22 therein so that the soap box will fit snugly within the flanges 20 and the overall soap dispenser 10 will be fixed in position about the box and not fall off during use thereof.

As may be readily seen, the receptacle portion 14 is designed to fit over one of the narrow sides of the soap box 21 which has therein a conventional dispensing spout opening 24 at the top of one of the narrow sides thereof. 10 Further it will be readily seen that the dispenser 10 is affixed to the box so that the spout 24 is opposite the measuring portion 18 of the dispenser 10.

Dividing the receptacle portion 14 and the dispenser portion 16 is a partition 26 which forms one side of a generally rectangular discharge spout in the lower portion of the dispenser 10 (see Figure 2). The top portion 26a of the partition 26 is inclined upward and outward away from the receptacle portion 14 and toward the measuring portion 18, its upper end being spaced from the flat top wall 25 of the dispenser 10 leaving a passage 26b opposite the spout opening 24 of the box. Partition 26 is glued or otherwise fixed to the side walls 27 of the container 12 to form a discharge chute 28. The bottom of the chute 28 formed by the partition 26 is open at 25a and permits discharge of the soap powder 30 therethrough into the washing machine and the like.

The soap measuring portion 18 of the dispenser 10 comprises a generally rectangular cup member located approximately opposite the upper end of the receptacle portion 14 so as to be in a position to receive soap dispensed from the conventional dispensing spout 24 on the soap box 21. The bottom wall 29 of the measuring portion 18 is curved so as to slope downward and inward toward the dispensing portion 16 with which it merges 35 to form one wall of the chute 28. The rectangular cup member conveniently may have a capacity of one cup with the suitable measurement markings 32 inscribed or otherwise etched on the walls 27 to indicate the amount of soap therein. Obviously other capacities could be 40 readily provided for.

In actual use the soap box 21 is opened in the usual manner so that soap may be poured from the spout 24. The dispenser 10 is then slipped over the edge with the measuring portion 18 opposite the spout 24. The box is 45 then tilted to the position shown in Figure 1 until the desired amount of soap, as indicated by the lines 32, flows out of the spout 24 into the measuring portion 18. The box is then tilted back to the upright position with the discharge spout 28a over the washing machine, sink or 50 the like and the soap previously measured in the measuring portion 18 falls downwardly under the influence of gravity and out the spout 28a into the machine. Any excess soap which may have been poured from the box 21 falls back into either the box 21 or into the space 34 55 above the partition 26 so that there is no spillage or wastage of the soap. On the next application the soap in the space 34 will flow into the measuring portion 18 and be dispensed as above. The dimensions of the measuring cup portion 18 are designed so that the desired 60 amount of soap, as indicated by the lines 32, will actually be dispensed at the discharge spout 28a taking into account any amount that may be caught by the partition 26 and fall back into the box or the space 34.

While I have shown the dispenser 10 having a receptacle portion 14 with four enclosed sides, it is obvious that the bottom edge 20 could be left off to accommodate a variety of sizes of packages. Generally speaking, however, the dispenser can be sufficiently economical to be provided with each different type of soap package, either 65 as a premium or a direct give-away.

I have thus provided a simple and economical soap dispenser that may be applied to the conventional soap box

without any necessity of special procedures or complicated application instructions and which will dispense soap in an improved and more economical fashion with less spillage and wastage.

While there is given above a certain specific example of this invention and its application in practical use, it should be understood that this is not intended to be exhaustive or to be limiting of the invention. On the contrary, this illustration and explanation herein are given in order to acquaint others skilled in the art with this invention and the principles thereof and a suitable manner of its application in practical use, so that others skilled in the art may be enabled to modify the invention and to adapt and apply it in numerous forms each as may be best suited to the requirement of a particular use.

I claim:

1. A soap dispenser for use with conventional cardboard soap boxes containing soap of the powdered or granulated type and having a spout opening therein at the top of one of the narrow sides thereof, comprising, in combination, a generally rectangular outer receptacle portion having at least partial front, rear, one side and bottom walls adapted to embrace the spouted side of said box; a tubular dispensing portion extending downwardly adjacent said receptacle portion and having an opening at the bottom thereof; and a measuring portion connected to and extending outwardly from the top portion of said dispensing portion; said side wall of said receptacle por-

tion having an opening therethrough registerable with the spout opening of said box whereby said measuring portion is below said spout opening when said box and dispenser are tipped 90°, and the bottom wall of said measuring portion sloping downwardly and inwardly and joining with the outer side wall of said dispensing portion whereby soap poured into the measuring portion drops through said dispensing portion when said box and dispenser are returned to their upright position.

10 2. The dispenser of claim 1 having a top portion of the side wall of said receptacle portion inclined upward and outward towards said measuring portion below said registerable opening, whereby any soap poured from said spout opening which does not reach said measuring portion upon return of the box to upright position is caught by said inclined top portion and is returned to the box.

15 3. The dispenser of claim 1 being made of translucent material and having scale markings on one wall of said measuring portion for measuring the soap poured from 20 said box to said measuring portion.
